WINDOW REGULATOR MECHANISM

Burton S. Floraday, Toledo, Ohio, assignor, by
mesne assignments, to Detroit Harvester Com-
pany, Detroit, Mich., a corporation of Michi-
gan

Application May 10, 1937, Serial No. 141,644
Renewed November 28, 1938

5 Claims. (Cl. 268—126)

This invention relates to window regulators for vehicles such, for example, as used in raising and lowering the windows of automobiles and is concerned with a regulator of the type shown and described in the application of Stanley W. Nicholson, Serial No. 132,738, entitled "Vehicle window regulator".

An object is to produce a vehicle window regulator of the above character in which the window moves to and from closed position at a uniform rate of speed and without any dwell or hesitation in its travel.

Another object is to simplify the regulator mechanism of the above type, particularly with reference to the mounting of the crank arm in such a manner that a sturdier and less expensive structure is provided.

A further object is to eliminate the clicking noise incident to a regulator of this structure at the time when the crank arm and link are brought into contact with each other during the raising and lowering movements.

For purposes of illustration, an embodiment of the invention is shown on the accompanying drawing in which

Figure 1 is a fragmentary elevation of a regulator operatively connected to the window glass, some of the parts being broken away for purposes of clarity;

Fig. 2 is a vertical sectional elevation substantially on the line 2—2 of Fig. 1;

Fig. 3 is a view similar to Fig. 1, showing the position of the parts substantially at the moment when the link is freed from engagement with its retainer or cam track;

Figs. 4, 5 and 6 are diagrammatic views showing the relative positions of the crank arm and link in various positions of adjustment, Fig. 4 showing the parts when the window is in raised position, Fig. 5 in an intermediate position similar to Fig. 3, and Fig. 6 in the lowered position of the window.

The illustrated embodiment of the invention comprises a window regulator having a triangularly shaped mounting plate 10 which is suitably secured as by bolts and nuts 11 to a lock board 12 of the usual type, which extends transversely of the vehicle door. Pivotedly mounted on the plate 10 on a stud 13 is a crank arm 14 formed with an inward extension 15 which pivotally engages the stud 13. The extension 15 projects inwardly into an opening 16 which is formed with an arcuate series of gear teeth 17, forming an internal gear, the teeth of which do not form a complete circle because of the finger extension 15.

Actuating the crank arm 14 is a pinion 18 which meshes with the teeth 17 of the internal gear and the pinion 18 is operatively connected to a shaft 19 through a clutch 20, the usual crank handle (not shown) engaging the shaft 19. Detailed description of the clutch 20 is not considered necessary since clutches of this character are old and well-known in the art. Suffice it to say that the clutch 20 enables the handle shaft 19 to be turned in either direction to raise or lower the window but retrograde movement of the pinion 18 is prevented, thereby retaining the window in its adjusted position.

Pivotedly connected to one end of the crank arm 14 is a link 21, the opposite end of the link 21 having a stud or roller 22, carrying a washer which is urged outwardly by a coil spring 23. The roller 22 fits into a horizontally elongate slot or guideway 24, one end of which is enlarged at 25 to enable insertion of the roller. The slot or guideway 24 is formed in a retainer 26 which is fixed to and depends from a channel member 27 which is rigidly secured to the lower edge of the window glass 28.

The link 21 is provided with a laterally projecting pin 29 and when the link is moved into abutment with the crank arm 14, the pin 29 is adapted to be disposed beneath an arcuately shaped flange 30 of a plate 31 which is fixed to the mounting plate 10. In this manner, the link 21 and crank arm 14 are maintained at a constant angle with respect to each other during a portion of the path of movement of the crank arm. Projecting in opposite directions from the crank arm 14 are ears 32 which are engaged by the link 21 when the link and arm are moved into engagement. In order to silence the click occasioned by the contact of these parts, a sleeve 33, of rubber or other suitable material, fits over the link and abuts against the ears 32.

Assuming the window glass 28 is in its uppermost or closed position, the parts assume the position shown in Figures 1 and 4. Upon turning the crank handle in a clockwise direction, to impart similar rotation to the pinion 18, the crank arm 14 is swung also in a clockwise direction, the link 21 being retained in its abutting relation to the crank arm by engagement of the pin 29 with the underside of the curved flange track 30. The window glass 28 is thus lowered and during this movement, the stud or roller 22 moves to the right of the figures in the slot or guideway 24. An important feature of this invention resides in so arranging the slot or guideway 24 that when the parts are in

the position indicated in Figs. 3 and 5, the roller 22 is substantially at the extreme right-hand end of the guideway 24. This militates against any lost motion between the roller 22 and guideway 24 at the time when the pin 29 leaves or enters beneath the flange 30. Empirically, it is found that if some stop or abutment is not provided for the roller 22 at this point, there is a dwell or interruption in the uniform rate of movement of the window glass 28. This is objectionable in the operation of windows for automobiles and other vehicles and it is found that if the roller 22 abuts against a stop at this point, the window glass can be actuated at a substantially uniform rate of speed. It will be apparent that upon continued turning of the crank handle, the arm 14 and link 21 will tend to straighten out substantially to the position indicated in Fig. 6 in which the window is open or in its lowered position. It will be apparent that upon turning of the crank handle or pinion 18 in the opposite direction, the above described operation is reversed, the link 21 first operating as a link until it is brought into abutting relation with the crank arm 14, whereupon these parts act together as a bell crank lever.

It is to be understood that numerous changes in details of construction, arrangement and operation may be effected without departing from the spirit of the invention especially as defined in the appended claims.

What I claim is:

1. A vehicle window regulator comprising a crank arm, an internal gear in said crank arm, a part of said arm projecting into the approximate center of the space formed by said internal gear, a pivotal mounting for said arm engaging said arm part, a manually operable pinion engaging said internal gear, a link connecting the end of said crank arm to the window, and means to cause said arm and link to act as a bell crank lever during a portion of the path of movement of the arm.

2. A vehicle window regulator comprising a crank arm, an internal gear in said crank arm, a part of said arm projecting into the space formed by said internal gear, a pivotal mounting for said arm engaging said arm part, a manually operable pinion engaging said internal gear, a link connecting the end of said crank arm to the window, means to cause said arm and link to act as a bell crank lever during a portion of the path of movement of the arm, and means

associated with the window for limiting the relative movement in one direction between the link and arm during another portion of the path of movement of the arm for effecting movement of the window at a uniform rate of speed.

3. A vehicle window regulator comprising a crank arm, an internal gear in said crank arm, a part of said arm projecting into the space formed by said internal gear, a pivotal mounting for said arm engaging said arm part, a manually operable pinion engaging said internal gear, a link connecting the end of said crank arm to the window, abutment means on said arm against which said link bears for a portion of the movement of said arm, a rubber sleeve on said link for silencing the contact between said arm and link, means to cause said arm and link to act as a bell crank lever during a portion of the path of movement of the arm, and means associated with the window for limiting the relative movement in one direction between the link and arm during another portion of the path of movement of the arm for effecting movement of the window at a uniform rate of speed.

4. A vehicle window regulator comprising a crank arm, a link connected to said crank arm, a retainer carried by the window having a horizontally elongate guideway, a stud on the free end of said link slidable in said guideway, a pin on said link, a stationary flanged track for receiving said pin to hold said link against movement relative to said arm thereby to cause the arm and link to act as a bell crank until said stud is approximately in horizontal alignment with the axis of said arm, and means for actuating said arm, the length of said guideway being so chosen that said stud abuts against an end thereof substantially prior to the pin entering or upon the pin leaving said track.

5. A vehicle window regulator comprising a crank arm, an internal gear in said arm, a part of said arm projecting into the space formed by said internal gear, a pivotal mounting for said arm engaging said arm part, a manually operable pinion engaging said internal gear, a link connecting the end of the crank arm to the window, and means forming part of the regulator adapted to interengage during a portion of the arm travel for holding said link and arm against relative movement thereby to cause the link and arm to act as a bell crank lever.

BURTON S. FLORADAY.
